ELECTRONIC SWITCH

William R. Baker, Berkeley, and Quentin A. Kerns, Oakland, Calif., assignors to the United States of America as represented by the United States Atomic Energy Commission

Application July 26, 1949, Serial No. 106,914

15 Claims. (Cl. 250—27.5)

1

The present invention relates to electronic switches capable of handling large amounts of power and is particularly related to both the construction and method of operation of an improved switch of this general type.

Numerous types of switches have been employed in the fields of electricity and electronics and of these, certain types, namely spark gaps, mercury vapor discharge devices, and hydrogen discharge devices have proven the most satisfactory for the switching of large amounts of power. Of these three, research has advanced hydrogen thyratrons as the most feasible in view of the multitudinous and exacting requirements which must be satisfied in addition to the requirement of large power rating. As a result of this research hydrogen discharge devices capable of passing a maximum pulsed anode current of approximately 350 amperes at 16 kilovolts are now known in the art. It appears that improvements in the techniques of tube construction and assembly may even double the power rating of these tubes and may also lengthen the life of these tubes. However, beyond this it appears that fundamental limiting factors preclude further improvements of hydrogen discharge devices of the type now known in so far as power ratings are concerned. For example, the destructive effects of inverse anode voltage limits not only the repetition rate of pulsed operation but also in part limits the maximum allowable forward anode voltage. Also the maximum current is in part limited by the amount of cathode emitting surface which may be made available, which in turn is limited by the practical limitations on size of the tube. Further undesirable limitations arise from the extensive control and baffling structure that has been found necessary to properly control discharge with a high potential impressed on the anode.

Thus in order to satisfy the ever increasing demands of industry for electric switches having larger and larger power ratings, it is necessary that some new and different apparatus be advanced which circumvents these present limitations.

It is therefore an object of the present invention to provide an improved method and apparatus for the switching of thousands of amperes of current.

It is another object of the present invention to provide an electric switch capable of operating at a high repetition rate without damage from high inverse plate voltage.

It is still another object of the present inven-

2

tion to provide an improved electronic switch capable of passing hundreds of megawatts of pulsed power.

5 A further object of the present invention is to provide an electronic switch of large power rating having a precisely controllable time of firing.

A still further object of the present invention is to provide an electronic switch wherein the current is substantially independent of emitting 10 surface limitations.

Yet another object of the present invention is to provide an electronic switch of the gaseous discharge type having only two main elements to support and control the discharge thereof.

15 Many other objects and advantages of the invention will become apparent from the following description taken in connection with the included drawing wherein Figure 1 is a sectional elevation of the switch taken on a median plane, Fig. 2 is 20 a sectional plan view of the switch taken as indicated by the line 2—2 of Fig. 1, and Fig. 3 is a diagram of electrical connections adaptable for use with the illustrated embodiment of the invention. With reference to Figs. 1 and 2, it may be 25 noted that the envelope of the present invention preferably consists of a base unit 1 and a plate 2 separated by an insulating cylinder 3. The base unit 1 is in the form of a cup or a cylinder with one end closed, and has a rim or flange 4 projecting outwardly therefrom about the circumference thereof a short distance from the open end. Upon this flange 4 rests the insulating cylinder 3 whose inner diameter is substantially equal to the outside diameter of the base unit whereby 30 lateral motion of the insulating cylinder with respect to the base unit is prevented when the insulating cylinder is resting upon the flange of the base unit. The plate 2 is also formed with a flange 6 about its periphery and the under surface of this flange rests upon the insulating cylinder 3 when the switch is assembled. Also, the outer diameter of the plate is substantially equal to the inner diameter of the insulating cylinder thereby preventing lateral motion therebetween 35 when assembled. The insulating cylinder 3 is separated from the flange 6 of the plate 2 by a gasket 5 and from the flange 4 of the base unit 1 by a similar gasket 10 thereby sealing off the interior of the envelope and making these connections gas tight and vacuum tight. The plate 2 40 may be provided with a circumferential slot in the flange thereof for the insertion of a small pipe 12 having inlet and outlet connections as shown in Fig. 1 and secured therein by any suitable means such as soldering. A similar pipe 11

45

50

55

also having inlet and outlet connections may also be secured to the under surface of the flange 4 on the base unit 1. These pipes may be utilized to carry cooling water for the purpose of aiding in the dissipation of heat generated in the device.

Interior to the envelope described above is a disc 7 mounted upon the base unit 1 and separating the interior of the base unit from the plate 2. The disc shown in the embodiment depicted in the drawing comprises a circular lid or cap engaging the open end of the base unit 1 and secured thereto by means of mutually cooperating threads on the periphery of the disc and the inner surface of the base unit wall; however, it will of course be appreciated that this disc may have a variety of configurations and may be secured in a variety of ways, all within the spirit and scope of the invention.

Further consideration of the illustrated embodiment of the disc 7 reveals that it is circular with a substantially square transverse opening formed in the approximate center thereof. Equi-spaced transverse keyways are formed along two sides of the square opening and a number of straight bars 8 are mated therein whereby the bars are firmly secured. These bars 8 define a number of identical parallel transverse slots 9 through the disc. It will of course be appreciated that various other modes of construction may be utilized, such as milling the slots directly in the disc 7 or inserting a slotted member in the disc.

The disc 7 is of particular importance to the present invention and care should be exercised not to confuse its function to that of a conventional grid electrode. The disc has two primary functions and acts in entirely different capacities when performing these functions as is set forth in detail hereinafter. In order to emphasize this point and also to refrain from referring to the disc as such, which is misleading inasmuch as the configuration is not limited to a disc-like shape, the disc has been given a particular name. The name chosen is biactor or in short, biactor, to indicate that it acts in two separate capacities. It is to be understood that this name has been coined to stand for the element 7 in this invention, and as used in the remainder of the specification and in the claims is intended to embrace all configurations and embodiments of the member 7 which falls within the scope of the present invention.

Interior to the base unit 1 is situated a trigger plate 21 which is mounted on a trigger support rod 22, which is in turn joined to a trigger supply lead 23. The base unit 1 is provided with an opening 24 through which the trigger supply lead projects. This opening 24 is threaded and has a shoulder thereabout against which rests a lead washer 26. A brass fitting 27 threadably engages the base unit 1 at the opening 24 and when totally engaged crushes the lead washer 26 between the shoulder on the base unit opening 24 and the fitting 27, thereby providing a gas tight seal at the opening 24. The trigger support rod 22 is attached to a trigger support nut 28 which is in turn threaded onto a metal bolt 29 and held in place by a lock nut 31. The bolt 29 has a circular portion removed from the head thereof to receive the end of a metal-glass seal 32, the other end of which is secured to the fitting 27. Metal shims 33 are inserted between the head of the bolt 29 and the trigger support nut 28 in order to properly center the trigger plate with respect to the walls of the base unit

1. The ion supply lead 23 thus supports the trigger plate 21 in position and insulates it from the base unit by the glass in the metal-glass seal. The trigger plate may be energized by a coaxial cable 35 which is inserted in the ion supply lead 23 and which is attached to a conical depression formed in the head of the bolt 29 as shown in Fig. 1. It will of course be appreciated that the details of the trigger supply lead are not vital to the invention and that any suitable element or combination of elements may be substituted therefor as long as the functions attributed thereto in the following disclosure are capable of being performed thereby.

15 In order for the present device to have a very rapid current rise at the point of firing it is necessary for the discharge to take place in an ionizable atmosphere. This atmosphere may constitute any one of a number of commercially 20 available gases or vapors; however, it has been found particularly advantageous to utilize low pressure hydrogen in this connection as deionization time is minimized thereby. The particular embodiment of the invention depicted in 25 the drawing employs circulating hydrogen which is preferably circulated through the device, as by the pipes 34 shown in Figs. 1 and 2, at a pressure of the order of a few hundred microns and continually filtered exterior to the device by any 30 suitable means (not shown). It will of course be appreciated that other gases or vapors such as helium may be utilized for this purpose; however, in general it is advantageous to employ an atmosphere in which the electron mean-free 35 path is a maximum and the deionization time is a minimum.

The surfaces of the plate 2 and the biactor 7 are parallel and the spacing therebetween is quite small as explained below. About this space 40 between the plate and disc is situated a guard ring 41 which may be maintained in position by any suitable means such as spring elements 42 attached thereto and bearing against the insulating cylinder 3 as shown in Fig. 2. The base 45 unit 1 has a stepped outer periphery about the top of its wall and the plate 2 has an inverted step periphery about its lower circumference as shown in Fig. 1, thereby providing a space for the placement of the guard ring 41.

50 The plate 2, base unit 1, and biactor 7 are preferably all formed of a metal having a high coefficient of heat conductivity, and furthermore are advantageously formed of a metal having a small amount of occluded gases. The property of good heat conductivity coupled with the cooling means described above prevents damage to the elements of the device under high power operation, and the absence of occluded gases is important in the prevention of contamination of the atmosphere within the device. Numerous metals satisfy 55 the above prerequisites with oxygen-free copper being one of the most available and least expensive. Also oxygen-free copper is not subject to the disintegration which results from the use of ordinary copper in a hydrogen atmosphere.

60 It may be further noted that the structure illustrated minimizes the lead inductance of the device which is particularly advantageous in certain applications employing pulsed operation.

65 It is to be noted that conventional elements are utilized to supply the operating potentials of the present invention, and thus no description thereof is included; however, the following is presented in combination with Fig. 3 as a brief description of the connections and potentials asso-

ciated with the device. The base unit 1, and consequently the biactor 7 to which it is electrically joined, is grounded. The positive operating potential of the invention is applied to the plate 2, and the trigger 21 is energized through the coaxial cable 35. The load is connected between the plate 2 and ground and for pulsed operation may constitute a pulse condenser 51 in series with the plate 2, and the primary of a pulse transformer 52 in series therewith to ground.

Considering now the operation of the invention, it is to be noted that the trigger electrode 21 is energized in order to produce a glow discharge in the space between the trigger electrode 21 and the biactor 7. The glow discharge may be produced by an alternating current voltage applied to the trigger electrode, or a direct current voltage may be utilized if adequate precautions are taken to confine the resulting glow discharge to the space provided therefor. The present embodiment utilizes a radio-frequency voltage as a lesser amount of voltage is required and also the rapid reversal of voltage polarity reduces the distance traveled by the electrons comprising the glow discharge and thus they are more easily contained in the space provided therefor. The glow discharge provides a large supply of electrons which are available to ionize the gas in the region between the anode and biactor; however, these electrons are prevented from ionizing the gas and constrained to remain in the space between the biactor 7 and the trigger electrode 21 by the action of the biactor. This member is at ground potential and by virtue of the ratio of the slot width to slot depth masks the trigger electrode from the plate 2, or in other words, the field from the positively charged plate 2 is prevented from extending down past the biactor by virtue of the constriction of the slots in the biactor, and thus not enough electrons pass through the biactor to cause critical ionization, that is, sufficient ionization to discharge the device. Therefore, prior to discharge, the device has a large supply of free electrons hovering over the trigger electrode and a highly positive potential upon the anode which is prevented from attracting these electrons by the action of the grounded biactor.

Discharge of the device is initiated by the application to the trigger electrode 21 of a negative voltage pulse having a fast rise time. The negative voltage pulse repels the free electrons forming the glow discharge and drives them toward the biactor 7. Thus, initially after application of the negative voltage pulse to the trigger electrode the biactor is likened to an anode with the free electrons moving toward it. However, a quantity of these electrons pass through the slots 9 in the biactor 7 and into the region influenced by the positive field about the plate 2 whereby they are forcefully attracted to the plate. The movement of a large number of free electrons from the vicinity of the trigger electrode 21 to the plate 2 ionizes the gas in the device. It is to be particularly noted at this point that the trigger electrode serves only to provide the initial supply of electrons in the glow discharge and to trigger the main discharge by repelling these electrons when energized by a negative voltage pulse. Following the initial ionization and breakdown the trigger electrode serves no further purpose. The trigger electrode is not a cathode within the generally accepted meaning of the term as it does not supply electrons during the course of dis-

charge or operation of the device, but to the contrary serves only to initiate the discharge.

The discharge of the device is in the nature of a glow discharge and the electrons forming the output current are produced by a number of interrelated actions. First, the ionization of the gas in the device frees a large number of electrons which are attracted to the plate 2 to form a part of the current. Second, the positive ions formed by the ionization of the gas in the space between the plate 2 and biactor 7 are attracted to the biactor 7 and owing to the action of the electric field between the plate and biactor impinge upon the biactor with sufficient velocity to produce secondary emission of electrons from the biactor which are also attracted to the plate to form a portion of the current. Third, the presence of a dense plasma between the plate 2 and biactor 7 results in field emission from the biactor which also produces a portion of the output current. It may be further noted that following initiation of discharge the presence of plasma allows the electric field from the plate to extend down into the slots in the biactor and even slightly into the space below the biactor. This results in an increase in the effective length of the field with the resultant production of more ion pairs than would ordinarily result in the limited space between the biactor and the plate. Thus the circuit of the device when conducting is from the biactor 7 to the plate 2, through the load and ground return to the biactor.

Particular requirements should be kept in mind with regard to the construction of the present invention. For example, the spacing between the biactor 7 and the plate 2 must be maintained less than the mean-free path of electrons in the atmosphere within the device in order that the atmosphere in this region will not be ionized by spurious free electrons. The biactor-plate spacing must also be maintained greater than a critical minimum at which an excess of field emission occurs from the biactor to the plate prior to triggering of the device. Thus the biactor-plate spacing may be easily computed for any particular device with a knowledge of the type of atmosphere, atmospheric conditions, and desired anode voltage. With regard to the biactor structure, it is also advantageous to limit the slot width to the same dimension as the biactor-plate separation in order to prevent premature discharge of the device as a result of ionization of the internal atmosphere. As an example of an electronic switch embodying the principles of the present invention the following data is presented: biactor-plate separation, 0.09, inch, biactor slot depth, $\frac{3}{8}$ inch; biactor slot width, $\frac{1}{16}$ inch; atmosphere, hydrogen at a pressure of 200-1000 microns of mercury; and plate voltage approximately 20 kilovolts.

It is to be noted that a number of factors tend to improve the firing characteristics of the device. With regard to the jitter time, or variations in the time after application of the trigger pulse that firing occurs, it is to be noted that it may be expressed as a function of the probability of free electrons causing ionization. This probability is dependent in part upon the energy imparted to the free electrons and in part on the number of free electrons provided. The present invention provides a tremendous reservoir of free electrons in the glow discharge above the trigger electrode and also insures that these

electrons will cause ionization by the fact that the energy imparted thereto by the field of the plate into which they are projected is far in excess of that necessary to produce ionization. Thus the probability of ionization is materially increased in the present device and the jitter time is consequently reduced; it being of the order of a few milli-microseconds.

A uniform discharge from the disc to the plate is insured by a combination of the following effects. In the first place the electron cloud forced up through the biactor by the trigger electrode penetrates all of the openings therein and thus initiates an even and uniform discharge from the disc. Also, if during discharge an arc should occur from one of the bars 8 of the biactor 7 to the plate 2, the voltage between the plate and this bar would immediately be reduced. Thus the higher voltage existing between the plate and the adjacent bars would immediately expand the discharge and extinguish the arc.

It is also to be noted that all spacing between metal and insulator cylinder is less than the mean-free path of electrons in the atmosphere internal to the device at the pressure maintained therein, thereby precluding the possibility of untimely ionization from stray free electrons. Furthermore, the possibility of breakdown across the insulator is minimized by placing the insulator metal contacts in relative field-free regions.

Thus a brief resume of the operation reveals that when the device is nonconducting a glow discharge is maintained above the trigger electrode 21 by the application of a small radio-frequency voltage thereto. The base unit 1 and attached biacting electrode 7 are maintained at ground potential and a highly positive potential is applied to the plate 2. The biactor 7 electrically masks the electrons forming the glow discharge from the strong electric field about the plate 2 and thus prevents critical ionization of the atmosphere within the device and thereby prevents discharge of the device. The device is rendered conducting by the energization of the trigger electrode with a pulse of negative voltage which drives the electrons comprising the glow discharge up through the slots in the biactor 7 and ionizes the atmosphere in the device. This overcomes the restraining action of the biactor and the biactor then assumes the opposite function of sustaining the discharge which continues until the polarity of the plate 2 is reversed.

From the foregoing disclosure of the invention it will be apparent to those skilled in the art that the present invention fulfills the objects specifically recited. An almost unlimited supply of electrons is produced within the device, both prior to and following the actual discharge. Thus jitter time is minimized and output current is maximized. Also as a result of the simple rugged construction of elements possible with the present invention the usual difficulties attending high current operation are eliminated. Furthermore, large inverse voltages do not materially affect the tube operation or life as the complicated, structurally weak elements of prior discharge devices have been eliminated and their successors are so constructed as to be relatively undamaged even by reverse discharge. Also the novel construction employed, the biactor structure in particular, enables the device to operate with a potential of the order of twenty kilovolts on the plate. Thus with a pulsed current capacity of the order of tens of thousands of amperes

the device is quite capable of handling hundreds of megawatts of pulsed power.

It will of course be appreciated that the potential purposes is substantially indestructible as times by the incorporation of minor structural variations within the scope of the invention. Any number of separated discs may be employed and under experiment the present device so modified has operated satisfactorily with 200,000 kilovolts applied to the plate. In this respect it may be noted that additional means such as suitable electrodes may be advantageously employed to reduce the electron velocity when operating with such high potentials.

15 The trigger plate 21 serves the purpose of supplying electrons to initiate the discharge of the device and it will be appreciated that numerous types of electrodes could be employed in this respect. An oxide-coated electrode could be employed; however, certain disadvantages are attendant upon this type of electron source. Also a loop of wire or a needle could be employed in place of the trigger plate; however, a plate 21, as shown, formed of a suitable material such as 20 tungsten has an extremely long life and for practical purposes is substantially indestructible as an electron source. Also the absence of sharp corners on the trigger electrode shown precludes a tendency of these corners to cause initial spotting of the discharge in the device and is thus 25 advantageous although not compulsory. It is also possible to eliminate the use of filament power by utilizing field emission from needle points by providing a large voltage pulse to the 30 points; however, although this may be advantageous in certain applications there are certain attendant disadvantages such as increased jitter time and the requirement of high trigger voltages.

35 40 Although the illustrated embodiment of the invention utilizes a circulating gas system, it is of course possible for a closed system to be used. With a closed system different insulating and clamping means may be advantageously employed and it may also be desirable to utilize a gas reservoir in such a system. However, only the application of basic electronic knowledge would be necessary in order to construct an electronic switch having a sealed system in accordance with the principles of the present invention and thus no further description of such an embodiment is included herewith.

45 50 While the foregoing description has set forth the preferred embodiment of the invention it will, of course, be apparent to those skilled in the art that many modifications are possible within the spirit and scope of the invention and it is not intended to limit the invention to the details disclosed except as may be defined in the following claims.

55 60 What is claimed is:

1. An electronic switch comprising an envelope containing an ionizable atmosphere, an anode, a trigger electrode, and a biacting electrode therebetween, said biacting electrode having apertures therethrough for the passage of ionizing discharge from said trigger electrode and being electron emissive only following ionization of said atmosphere thereby to support electrical discharge to said anode.

electrode within said envelope separating said plate and said trigger electrode, said biacting electrode having transverse slots therethrough and being separated from said plate by a distance less than the mean-free path of electrons in the atmosphere of said envelope at the pressure therein.

3. An electronic switch comprising a gas-tight envelope containing a low pressure atmosphere of ionizable gas, a trigger electrode controllably providing high velocity electrons to initiate ionization of said atmosphere, a biacting electrode preventing ionization of said atmosphere in the absence of said high velocity electrons and sustaining an electric discharge following the provision of said high velocity electrons, and a plate for the receival of said discharge.

4. The combination comprising an envelope containing an ionizable atmosphere, an anode having a highly positive potential impressed thereon, an electron source in close proximity with said anode, a biacting electrode separating said anode from said ion source, said biacting electrode being maintained at substantially the same potential as said electron source and having slots of a large depth to width ratio therein for the passage of electrons whereby said electrons are restrained from reaching said anode, and means impressing a negative potential upon said electron source, thereby imparting a high velocity to said electrons for overcoming the restraining action of said biacting electrode.

5. An electronic switch comprising an envelope containing an ionizable atmosphere, an anode, a trigger electrode acting to ionize said atmosphere, and a biactor restraining ionization of said atmosphere prior to the action of said trigger electrode and sustaining electric discharge between said biactor and said anode following the ionizing action of said trigger electrode.

6. An electronic switch comprising an envelope containing an ionizable atmosphere, an anode maintained at a highly positive potential, an electron source maintained at substantially ground potential and having a further controlled negative potential instantaneously impressed thereon whereby said atmosphere is ionized, and a biacting electrode between said anode and electron source, having openings therethrough of a large depth-to-width ratio whereby said electron source is electrically masked from said anode prior to ionization of said atmosphere, said biacting electrode being maintained at a substantially ground potential thereby supporting electric discharge to said anode following ionization of said atmosphere.

7. An electronic switch comprising an envelope containing an ionizable atmosphere and three electrodes, the first of said electrodes being maintained at a positive potential, the second of said electrodes comprising a source of electrons and having a controlled negative potential instantaneously impressed thereon, and said third electrode being interposed between said first and second electrodes and having openings therethrough for the passage of said electrons, said openings being constricted to control said electron passage and thereby control ionization of said atmosphere and said third electrode being grounded whereby electric discharge is maintained between said first and third electrodes following ionization of said atmosphere.

8. An electronic switch comprising an envelope containing an ionizable atmosphere, an anode, a trigger electrode operating solely to initiate ionization of said atmosphere, and a perforated

biacting electrode disposed between said anode and said trigger electrode, said perforations being constricted to prevent ionization of said atmosphere prior to the operation of said trigger electrode, and said biacting electrode being maintained at a negative potential with respect to said anode whereby electric discharge is maintained therebetween following ionization of said atmosphere.

9. A method of switching electrical energy comprising the steps of establishing a potential difference region in an ionizable atmosphere, producing an electron glow discharge, preventing electrical energy transfer by establishing a field-free region and separating said glow discharge from said potential difference region by said field-free region, and causing electrical energy transfer by accelerating the electrons of said glow discharge toward said potential difference region through said field-free region thereby ionizing said atmosphere and supporting electron discharge across said potential difference region by supplying electrons from said field-free region.

10. An electronic switch comprising an envelope containing an ionizable atmosphere, a positively charged anode grounded through a load, an electron source at a negative potential with respect to said anode, a grounded biacting electrode separating said anode and said electron source and electrically masking said electron source from the positive potential of said anode, said biacting electrode having constricted transverse openings therethrough for the passage of an ionizing discharge, and trigger means controllably accelerating electrons from said electron source toward said biacting electrode whereby an ionizing discharge is produced through said biacting electrode and electrical discharge is maintained between said anode and said biacting electrode.

11. An electronic switch comprising an envelope containing an ionizable atmosphere, a planar anode within said envelope and having a large heat capacity, a planar perforated biacting electrode disposed adjacent and parallel to said anode, said biacting electrode having a large heat capacity and being of rugged construction, and a trigger electrode separated from said anode by said biacting electrode and thereby electrically masked from said anode, said trigger electrode producing electrons for ionization of said atmosphere between said anode and biacting electrode upon the impression of a trigger voltage thereto, and said biacting electrode and anode being adapted to sustain electric discharge therebetween over the entire mutually presented faces thereof upon ionization of said atmosphere.

12. An electronic switch as claimed in claim 11 further characterized by said anode and biacting electrode being formed of copper.

13. An electronic switch comprising an envelope containing an ionizable atmosphere, an anode having a large planar surface, and a biacting electrode having a large planar surface in close proximity with and parallel to the planar surface of said anode, said biacting electrode having apertures therethrough for controlling the passage of an ionizing electron discharge and said anode and biacting electrode being adapted to have a large potential difference impressed therebetween whereby electric discharge is maintained between the adjacent planar surfaces thereof following ionization of said atmosphere.

14. An electronic switch comprising an envelope containing an ionizable atmosphere, a trigger electrode emitting electrons, an anode at

a high positive potential relative to said trigger electrode, and a perforated biacting electrode disposed intermediate said anode and trigger electrode and electrically masking said trigger electrode from said anode for a maximum potential difference therebetween and supporting electrical discharge to said anode for some greater potential difference causing ionization of said atmosphere.

15. A method of electronic switching in an ionizable atmosphere comprising establishing a first region having a high potential gradient therethrough and having a dimension in the direction of said gradient of less than the mean free path of electrons in said atmosphere, establishing a second region adjacent said first region and having a substantially zero potential gradient therethrough, controllably introducing copious quantities of high velocity electrons into said second region and directed toward said first

region whereby ionization of said atmosphere is accomplished, and subsequently maintaining electric discharge across said first region.

WILLIAM R. BAKER,
QUENTIN A. KERNIS.

Certificate of Correction

Patent No. 2,535,886

December 26, 1950

WILLIAM R. BAKER ET AL.

It is hereby certified that error appears in the printed specification of the above numbered patent requiring correction as follows:

Column 5, line 35, for "he" read *the*; column 8, line 4, for "tical purposes is substantially indestructible as" read *tial rating of the device may be multiplied many*;

and that the said Letters Patent should be read as corrected above, so that the same may conform to the record of the case in the Patent Office.

Signed and sealed this 24th day of April, A. D. 1951.
